UNITED STATES PATENT OFFICE

JAMES D. LE VAN, OF MILWAUKEE, WISCONSIN, ASSIGNOR TO CUTLER-HAMMER, INC.,
OF MILWAUKEE, WISCONSIN, A CORPORATION OF DELAWARE

CONTROL FOR ELECTRON TUBES

Application filed October 12, 1929. Serial No. 399,142.

This invention relates to control of electron tubes and is especially applicable to tubes of the type disclosed in my copending application Serial 319,918, filed Nov. 16, 1928.

An object of the invention is the control of an electron discharge tube of the gaseous type by applying to the grid of the tube a variable instantaneous potential so as to cause discharge between the main electrodes to start at different moments of the positive half cycle depending upon the moment at which the instantaneous voltage on the grid reaches a certain value relative to the voltage between the main electrodes.

15 Electron tubes of the gaseous type in which the discharge to the anode is controlled by an auxiliary electrode or grid are well known in the art. In the past the anode current was controlled so as to increase or decrease in response to and directly in accordance with an increase or decrease of a positive potential impressed upon the grid. A negative potential impressed upon the grid always prevented the start of the discharge between the 25 main electrodes. I have disclosed in my aforementioned copending application a tube in which the main discharge is controlled by impressing upon the grid a variable negative potential so that no substantial current flows 30 to the anode while the grid potential is of a relatively low negative value, but that the discharge to the anode starts suddenly when the negative potential of the grid reaches a certain higher value which value is dependent upon the design of the tube and the instantaneous value of the potential between main electrodes.

The accompanying drawings illustrate several embodiments of my invention.

40 Fig. 1 illustrates the control of the main discharge by applying an adjustable direct current potential to the grid.

Fig. 2 shows diagrammatically the voltage and current relations in the tube.

45 Fig. 3 shows another embodiment of my invention wherein the moment of application of a high negative potential to the grid is varied relative to the time phase of the alternating voltage impressed upon the main electrodes.

Fig. 4 shows the operation of the system disclosed in Fig. 3.

Fig. 5 shows still another system in which the grid potential is alternating and the time phase of said grid potential is varied relative to the time phase of the potential between the main electrodes.

Fig. 6 shows diagrammatically the current and voltage relations of the system illustrated in Fig. 5.

Referring to Fig. 1 the numeral 1 denotes a gaseous discharge tube having an anode 2, a grid 3, a cathode 4 and an auxiliary electrode 6, the purpose of which is to maintain a discharge between itself and the cathode 4, 65 which discharge is supplied with current by the battery 7, the current being regulable through a resistance 8.

A source of alternating current 9 has one terminal connected with the anode 2 by 70 means of conductor 10, while its other terminal is connected by means of conductor 11 to translating device 12, which in turn is connected by conductor 13 and the leading-in wire 5 to cathode 4. A battery 14 which is 75 paralleled by a potentiometer resistance 15 has its negative pole connected to the grid 3 and its positive pole to cathode 4.

If now an alternating current of a certain potential is applied between the cathode 4 and 80 the anode 2 while the grid potential is zero, current will start during the half cycle when the anode 2 is positive at the moment when the alternating voltage has reached a value which is dependent upon the characteristic of 85 the tube. Such current will then continue to flow until the positive voltage of the anode 2 has again decreased to substantially zero value. During the next half cycle the anode 2 is negative and therefore no current can 90 flow through the tube, while during the third half cycle the polarity of the anode is again positive and current will flow as described heretofore.

I have found that if the grid 3 is given a 95 relatively high negative potential with respect to the cathode by adjustment of the potentiometer 15, the positive voltage which is required on the anode 2 to start the discharge through the tube is thereby decreased, 100

so that the moment at which the current starts to flow during the positive half cycle can be advanced at will. It is thus possible, by varying the negative grid potential, to regulate the total amount of energy which passes through the tube during a half cycle and thus also the total amount of energy which passes through the translating device 12.

Figure 2 illustrates the operation of the device. The curve S represents one cycle of the alternating potential which is impressed between the anode and the cathode. It has been observed that the glow potential of the tube varies somewhat with the potential S. If a potential Eg^1 , which is negative with respect to the cathode, is impressed upon the grid of such a value that for any given instantaneous potential between the main electrodes, the instantaneous voltage between 2 and 3 is less than the glow voltage, no glow discharge is initiated between the grid and the anode and thus no current starts to flow between the main electrodes. If a higher negative potential Eg^2 is impressed upon the grid of such a value that the maximum resultant voltage between 2 and 3 is just equal to the glow voltage of the tube at the moment when the main voltage attains its maximum instantaneous value, current flow between the cathode and anode is initiated at the moment B resulting in a current wave shown approximately by the curve BCF. If the grid voltage is still further increased to the value Eg^3 so that it is equal to the glow voltage of the tube for substantially zero main voltage, the flow of current between the main electrode is initiated at the moment A resulting in a current represented by the curve ADF.

In Fig. 3, 20 is the electron discharge tube having the cathode 21 and anode 22. The grid 23 and the auxiliary electrode 24 which is supplied with current from the battery 25 and the characteristics of the tube are the same as those of the tube 1 shown in and described in connection with Fig. 1. 26 is a source of alternating current energy, while 27 is a translating device the current of which is to be controlled by grid 23. A synchronous motor 28 is supplied with energy from the source 26 so that its armature rotates in synchronism with the current supplied to the tube. The motor drives a rotating commutator 29 which has a continuous segment 29a and connected therewith an interrupted segment 30 making contact with the brushes 31 and 32 respectively.

The brush 32 may be revolved so that the moment at which it makes contact with segment 30 during each revolution may be varied. Batteries 34 and 35 supply the necessary potentials to the grid 23. A resistance 33 is connected across the brushes 31 and 32.

Referring to Figs. 3 and 4 the device operates in the following manner:

If E is the alternating potential impressed

between the cathode 21 and anode 22 and Eg^4 is the minimum negative grid potential supplied by the battery 34 which is assumed not to be sufficient to start a discharge between main electrodes, the rotation of the commutator causes at the moment t_1 contact between brush 32 and segment 30 and thus the joint voltage of batteries 34 and 35 is applied to the grid 23. The voltage Eg^5 is sufficient to cause ignition of the main arc and a current is caused to flow which is represented by the curve IL' in Fig. 4. If now the brush 32 is rotated counterclockwise so that the voltage Eg^5 is not applied until the time t_2 has elapsed from the moment when the voltage E passed through zero, ignition is delayed and the resulting current during the corresponding half cycle is represented by IL' in Fig. 4.

The resistance 33 is inserted to prevent a short circuit of the battery 35 at the time when the brush 32 makes contact with segment 30.

The system illustrated in Fig. 5 employs an electron tube 40 which may be of the same construction as the tube illustrated in Fig. 1. L', L2 and L3 are power lines supplying three phase alternating current. The tube 40 and the translating device 46 are connected between lines L2 and L3. An induction regulator 47 having the polyphase primary winding 48 and the rotatable secondary single phase winding 49 is also connected to lines L', L2 and L3. A rectifier element 50 of any well known type is inserted in the connection between the secondary winding 49 and the grid 43, so that only the negative half waves of the current induced in the winding 49 can pass to the grid 43. The battery 51 which is connected in series with the limiting resistor 52 between the cathode 41 and the grid 43 serves to maintain the grid 43 at the minimum negative potential at which no discharge can take place between the main electrodes. The alternating voltage induced in the secondary winding 49, which is impressed upon the grid of the tube may be varied in phase relative to the time phase of the voltage impressed upon the main electrodes.

Fig. 6 shows the operation of the system. E' is the voltage impressed upon the main electrodes of the tube while Eg^6 is the voltage impressed upon the grid of the tube by the battery 51. Eg^7 is the alternating voltage impressed upon the grid of the tube for a certain position of the induction regulator secondary winding. As long as the voltage Eg^7 is negative and below the glow voltage of the tube during that half cycle when the voltage E' is positive, no discharge can take place between the main electrodes. At the moment t_3 the sum of the voltage Eg^7 and the main voltage E' is equal to the glow voltage of the tube and a discharge takes place between the main electrodes. The current

during the remainder of the half cycle is represented by the curve IL^3 . If now the secondary winding 49 is rotated so that the voltage impressed upon the grid is advanced in phase relative to the main voltage as represented by curve Eg^3 the glow voltage is reached at the earlier moment t_4 of the half cycle. Ignition takes place at this earlier moment, and the current which passes between the main electrodes during the corresponding half cycle is represented by the curve IL^4 .

While I have shown a number of embodiments of my invention for the purpose of describing the same, it will be apparent that many other variations of the system are possible without departing from the scope of the invention.

Thus two tubes which control alternate half cycles or a double tube may be employed for controlling a single phase current or several tubes or polyphase tubes for the control of polyphase currents.

What I claim as new and desire to secure by Letters Patent is:

1. An electron discharge tube containing an ionizable gas and having associated with its anode a grid effective when supplied with a relatively low potential negative with respect to the cathode to prevent discharge between the main electrodes and to aid initiation of such discharge by producing a glow discharge between the grid and anode when said negative grid potential has a relatively high value.

2. An electron discharge tube containing an ionizable gas and having associated with its anode a grid supplied with a variable potential negative with respect to the cathode and effective to start a discharge between the main electrodes by producing a glow discharge between the grid and anode when the potential between the grid and the anode attains a given value.

3. An electron discharge tube containing an ionizable gas and having associated with its anode a grid supplied with a relatively low potential negative with respect to the cathode to prevent discharge between the main electrodes and means to temporarily increase said negative grid potential to produce a glow discharge between the grid and anode and to thereby initiate said first-mentioned discharge.

4. An electron discharge tube containing an ionizable gas and having associated with its anode a grid supplied with a relatively low potential negative with respect to the cathode to inhibit discharge between the main electrodes and means to increase said negative potential at a given moment to produce a glow discharge between the grid and anode and to thereby initiate said first-mentioned discharge.

5. An electron discharge tube supplied with an oscillating potential, containing an

ionizable gas and having associated with its anode a grid effective when supplied with a variable potential negative with respect to the cathode, to produce a glow discharge between the grid and anode, for reducing the starting potential of the tube in accordance with said grid potential.

6. An electron discharge tube supplied with an alternating potential, containing an ionizable gas and having associated with its anode a grid effective when supplied with a variable potential negative with respect to the cathode, to produce a glow discharge between the grid and anode, for reducing the starting potential of the tube in accordance with said grid potential.

7. An electron discharge tube supplied with an alternating potential containing an ionizable gas and having associated with its anode a grid effective when supplied with a variable unidirectional potential negative with respect to the cathode, to produce a glow discharge between the grid and anode, for reducing the starting potential of the tube in accordance with said grid potential.

8. The method of controlling the operation of an electron discharge tube containing an ionizable gas and having associated with its anode a grid, which consists in supplying said grid with a potential negative with respect to the cathode, capable of producing a glow discharge between the grid and anode and thereby reduce the potential required for initiation of discharge.

9. The method of controlling the discharge of an electron tube having a varying potential impressed between its anode and cathode, containing an ionizable gas and a grid associated with its anode, which consists in supplying said grid with a potential negative with respect to the cathode, capable of producing a glow discharge between the grid and anode to reduce the starting potential and varying said grid potential to thereby control said starting potential.

10. The method of controlling the discharge of an electron tube which is supplied from an alternating source, containing an ionizable gas and a grid associated with its anode, which consists in supplying said grid with a potential negative with respect to the cathode, capable of producing a glow discharge between the grid and anode to reduce the starting potential and varying said grid potential, to thereby control the instantaneous discharge starting voltage of alternating half cycles.

11. The method of controlling the discharge of an electron tube which is supplied from an alternating source, containing an ionizable gas and a grid associated with its anode, which consists in supplying said grid with a constant potential negative with respect to the cathode to reduce the starting potential and regulating said grid potential.

to thereby produce a glow discharge between the grid and anode and control the instantaneous discharge starting voltage of alternative half cycles.

- 5 12. The method of controlling the discharge of an electron tube which is supplied from an alternating source, containing an ionizable gas and a grid associated with its anode, which consists in supplying said grid
10 with a low potential negative with respect to the cathode to inhibit discharge between the main electrodes and raising this negative potential at a desired moment to a higher value which produces a glow discharge between the
15 grid and anode to thereby initiate said discharge at that moment of the alternating cycle.

In witness whereof, I have hereunto subscribed my name.
